UNITED STATES PATENT OFFICE.

THOMAS O. THEOBALD, OF DETROIT, MICHIGAN.

WASHING MACHINE.

Application filed June 4, 1921. Serial No. 474,989.

To all whom it may concern:

Be it known that I, THOMAS O. THEOBALD, a citizen of the United States, and residing at Detroit, in the county of Wayne and 5 State of Michigan, have invented a new and Improved Washing Machine, of which the following is a specification.

This invention relates to washing machines of the vacuum-cup type, and its object is to 10 provide a portable machine of this character which may be used in connection with any convenient tub, water-tight box or barrel which is sufficiently large to receive the base of the machine.

15 This invention consists in a base, a pedestal, a cross head and a pair of vacuum-cups 20 whereby the cups may be moved up and down on the pedestal.

It further consists of the novel gearing and the connecting mechanism between the 25 gearing and the cross head whereby the rotary movement of the gearing may be translated into reciprocating movement of the cups, and in means for attaching and detaching the cups from this connecting mechanism.

30 It also consists in the details of construction illustrated in the accompanying drawing and particularly pointed out in the claims.

In the drawings, Fig. 1 is a view, one half 35 in elevation and one half in central vertical section, of this improved washing machine.

Fig. 2 is a central vertical section of the 40 operating gearing and the casing therefor at right angles to the plane of Fig. 1. Fig. 3 is a plan of a base on the line 3—3 of Fig. 1. Fig. 4 is a vertical section of the bottom of the pedestal at right angles to the plane of Fig. 1. Fig. 5 is a view of a modified 45 type of washing machine. Fig. 6 is a section on the line 6—6 of Fig. 3.

Similar reference characters refer to like parts throughout the several views.

The machine shown embodies an electric motor 1 at the top of the gear case and 50 having a carrying handle 2, the motor shaft having a square end 3 (Fig. 1) extending into the shaft 4 of the worm 5. A short bearing 6 for this shaft 4 may be positioned next

to the motor casing which is connected to the gear casing by screws 7. As no claim is 55 made to the details of the motor, it is shown conventionally.

The gear casing is of two parts 8 and 9 connected by bolts 10. At its upper end (Fig. 2) is a sleeve 12 in which are mounted 60 the bearings 6 and 13 for the worm shaft 4, the lower being preferably a ball bearing. A pair of bosses on this sleeve 12 constitute bearings for the shaft 14 which carries a worm wheel 15 and a spur pinion 16 which 65 meshes with the large gear 17 on the shaft 18. This gear has a bearing 19 for the pin 20 extending from the block 21 which is transversely slidable in a two-part yoke 22. The opposite end of this shaft is preferably 70 squared so that it may drive a wringer 23 of any desired character which may be attached to the part 8 of the gear casing by screws 24.

Vertically slidable in the upright tubular 75 pedestal 26 is a sleeve 27 which is formed with longitudinal slots 28 at its upper end which divide the upper end of the sleeve into two parts, to each of which a portion of the two-part yoke 22 is connected. The slots 80 28 are sufficiently wide to permit the shaft 18 to pass through, and the slidable block 21 is sufficiently long to bridge the space between the two parts of the yoke 22. The sleeve 27 may therefore be forced up and 85 down by the slidable block 21 as it travels around in a circle with the pin 20, passing across the gap between the two parts of the yoke 22 centrally above and below the 90 shaft 18.

The pedestal connects to a base of any desired character. I have shown a shallow pan 31 having a rim 32, ribs 33 formed with slots 34, and a central thimble 35 provided with a radial pin 36 adapted to enter the 95 bayonet slots 37 in the lower end of the pedestal to hold it in position. I prefer to form the thimble of a separate and heavier piece of metal and attach its lower flange 38 to the base by spot welding. A circular spring 100 39 having a hump 40 restrains undesired movement between the pedestal and base.

The gear casing fits onto the upper end of the pedestal 26, the pedestal being gripped by the hubs 42 by reason of the bolts 43 and 105 nuts 44 provided with handles 45. Slidable

- on the pedestal is a cross head consisting of a collar 46 and the arms 47 provided with pins 48 at their ends to extend through the rectangular bosses 49 on the vacuum-cups 50. These cups are held in proper position by the springs 51 mounted on pins 53, but permitted to swing on the pins 48 by these springs when unequal stresses come on the cup because of the clothes in the tub.
- 10 The sleeve 27 is provided with any desired number of recesses 55 which are adapted to receive a pin 56 mounted on the inner end of a bar 57. A lever 58 mounted on a pin 59 and connecting to the bar 57 by a pin 60 is normally held in the position shown in Fig. 1 by the spring 51 and a link 62 supports the bar 57. The pedestal 26 has a longitudinal slot 64 to permit the pin 56 to move up and down. When the lever 58 is swung up, the pin 56 is withdrawn from its recess 55 and the collar 46 and the cups mounted thereon may be adjusted vertically on the sleeve 27. The machine may be made quite light so it can be placed in any convenient 25 container and operates whenever current is turned on.

In Fig. 5 I have shown the gear case 9, motor 1 and handle 2 but the hub 42 of the gear case connects to the cross bar 72 which 30 extends across the receptacle 71. The sleeve 70 which carries the vacuum cups 73 is quite short so that it does not extend down below the cups. A properly designed machine of small size can be mounted on a large dish pan or foot bath.

While I have conventionally shown an electric motor, I do not wish to be limited thereto, as I wish the term "motor" to include all types of driving devices which may be desirable for actuating the cup support. While two cups are shown, any desired number may be used, and one of those shown may be omitted if desired.

The details of construction and the proportions of the parts may all be changed by those skilled in the art without departing from the spirit of my invention as set forth in the following claims.

I claim:

- 50 1. In a washing machine, the combination of a base, a pedestal extending upward therefrom, a gear case mounted on the upper end of the pedestal, a motor on the gear case, a cross head slideable on the pedestal, a pair of vacuum-cups mounted on the cross head, and means mounted in the gear case and pedestal operatively connecting the motor and cross head.
- 60 2. In a washing machine, the combination of a base, a pedestal extending upward therefrom, a gear case mounted on the upper end of the pedestal, a motor on the gear case, a cross head slideable on the pedestal, a pair of vacuum cups mounted on the cross head, and a sleeve slideable in the pedestal, means con-

necting the cross head to the sleeve, and means operatively connecting the motor and sleeve.

3. In a washing machine, the combination of a base, a pedestal extending upward therefrom, a gear case mounted on the upper end of the pedestal, a motor on the gear case, a cross head slideable on the pedestal, a pair of vacuum cups mounted on the cross head, a sleeve slideable in the pedestal, means connecting the cross head to the sleeve, means operatively connecting the motor and sleeve embodying a yoke at the upper end of the sleeve and having a transverse guide groove, a block slideable in the groove, a pin in said block, a gear in which said pin is mounted, and means connecting the motor and gear.

4. In a washing machine, the combination of a base, a pedestal extending upward therefrom, a gear case mounted on the upper end of the pedestal, a motor on the gear case, a cross head slideable on the pedestal, a pair of vacuum cups mounted on the cross head, a sleeve slideable in the pedestal, means connecting the cross head to the sleeve, means operatively connecting the motor and sleeve embodying a yoke at the upper end of the sleeve and having a transverse guide groove, a block slideable in the groove, a pin in said block, a gear in which said pin is mounted, means connecting the motor and gear, and a shaft for said gear, said sleeve and yoke having slots through which said shaft may extend.

5. In a washing machine, the combination of a base, a pedestal extending upward therefrom, a gear case mounted on the upper end of the pedestal, a motor on the gear case, a cross head slideable on the pedestal, a pair of vacuum cups mounted on the cross head, and means mounted in the gear case and pedestal operatively connecting the motor and cross head, said cross head embodying oppositely extending arms having pins in their outer ends, said vacuum-cups having bosses through which the pins extend, and spring to hold the cups in position.

6. In a washing machine, the combination of a base, a pedestal extending upward therefrom, a gear case mounted on the upper end of the pedestal, a motor on the gear case, a cross head slideable on the pedestal, a pair of vacuum cups mounted on the cross head, a sleeve slideable in the pedestal, means connecting the cross head to the sleeve, and means operatively connecting the motor and sleeve, said pedestal having a longitudinal slot and said cross head having a pin extending through said slot into a recess in said sleeve.

7. In a washing machine, the combination of a rotatable shaft, a frame to support the shaft, a member adapted to slide in the frame and having its line of movement intersecting the axis of the shaft, a cross head on said

slidable member and having a slot to permit the passage of the shaft and a guide groove at an angle to said slot and formed of two parts, one on each side of the slot, a block 5
slidable in said groove and of sufficient length to bridge said slot, a crank on the shaft, a crank pin carried thereby and adapted to engage said block, and means to rotate the shaft.

10 8. In a washing machine, the combination of a gear case, a motor mounted on the gear case, a sleeve extending down from said gear case, a cross head attached to said sleeve, vacuum cups attached to said cross head, 15 means operatively connecting the motor and sleeve to cause the cross head and cups to move up and down, a support for said gear case, said connecting means embodying a

yoke at the upper end of the sleeve and having a transverse guide groove, a block slid- 20
able therein, a gear having a crank pin en-
gaging said block, and means connecting the
gear to the motor embodying a worm con-
nected to the motor shaft, a transverse shaft,
a worm gear thereon meshing with the worm 25
and a pinion on said shaft meshing with said
gear.

9. In a washing machine, the combination of a base, a pedestal extending upward there- 30
from, a gearing support at the upper end of the pedestal, a motor on the support, a cup support slidable on the pedestal, a vacuum cup mounted on the cup support, and means operatively connecting the motor and cup support.

THOMAS O. THEOBALD.
